UNITED STATES PATENT OFFICE.

JULIUS KINDERVATER, OF RICHMOND, VIRGINIA, ASSIGNOR TO LOCOMOTIVE SUPER-HEATER COMPANY, OF NEW YORK, N. Y., A CORPORATION OF DELAWARE.

LOCOMOTIVE WITH SUPERHEATER.

1,181,392.

Specification of Letters Patent. Patented May 2, 1916.

Application filed April 30, 1912. Serial No. 694,120.

To all whom it may concern:

Be it known that I, JULIUS KINDERVATER, a citizen of the United States, residing at Richmond, in the county of Henrico and State of Virginia, have invented certain new and useful Improvements in Locomotives with Superheaters, of which the following is a specification.

This invention relates to locomotives, and more particularly to locomotives equipped with superheaters, although in some of its aspects the invention is equally applicable to locomotives in which no superheater is employed.

More specifically the invention relates to superheaters of the Schmidt type which comprise a header located in the smoke box and superheater tubes arranged within the fire tubes of the boiler and connected with the header.

One object of the invention is to provide an improved construction of header, and also a novel and efficient method of securing the superheater tubes thereto.

A further object is to provide an improved arrangement of throttle valve for controlling the flow of steam to the engine cylinders.

A still further object is to provide means for causing steam to circulate from the boiler through the superheater and back into the boiler whenever the flow of steam to the engine is interrupted, thereby preventing burning of the superheater tubes, and dispensing with the necessity for the use of dampers hitherto employed.

In order that the various features of my invention may be readily understood reference is had to the accompanying drawings forming part of this specification, and in which,

Figure 1 is a central longitudinal section through a portion of a locomotive boiler showing one form of header in position in the smoke box and my improved throttle valve connected therewith, as well as the means for securing circulation of steam through the superheater, as described; Fig. 2 is a front view of the superheater header and tubes, the throttle valve and boiler shell being in section on the line 2—2 of Fig. 1; Fig. 3 is a central longitudinal section through my improved throttle valve casing; Fig. 4 is a central longitudinal section through the auto-

matic circulating valve, hereinafter described; Fig. 5 is a view similar to Fig. 1, taken on the line 5—5 of Fig. 7, showing a modified form of header structure; Fig. 6 is a plan view of the header shown in Fig. 5, 60 the tube sheet of the boiler being in section; Fig. 7 is a front elevation of the superheater shown in Fig. 5, the boiler shell being in section; Fig. 8 is a longitudinal section on an enlarged scale of my improved joint for the superheater tubes; Fig. 9 is an enlarged sectional detail substantially on the line 9—9 of Fig. 7 showing the method of attaching the superheater tubes to the header; Fig. 10 is a similar view at right angles to Fig. 9, 70 the header being in section on the line 10—10 of Fig. 5; Figs. 11 and 12 are fragmentary detail views showing a sectional elevation and a sectional plan, respectively, of the improved tap bolt which I employ; Fig. 13 is a 75 vertical longitudinal section through still another form of header which I may employ; Fig. 14 is a sectional plan view taken substantially on the line 14—14 of Fig. 13 looking in the direction of the arrow and 80 showing the superheater tubes connected to the header; and, Fig. 15 is a sectional plan view, on a reduced scale, showing a slightly modified form of the header illustrated in Figs. 5, 6 and 7.

Referring to the drawings in detail and first more particularly to Figs. 1 and 2, the boiler shell is designated by the numeral 1 and the usual steam dome by the numeral 2. 3 designates the dry pipe which extends 90 inside the boiler shell from the steam dome to the smoke box, and, passing through the tube sheet 7, is provided with a fitting 3^a adapted to be connected with a superheater header. The header shown in Figs. 1 and 2 95 comprises three compartments, 4, 5 and 6, all extending parallel with each other and with the tube sheet 7. The compartment 4 is provided with an intake nozzle terminating in a flange 4^a adapted to engage the fitting 3^a of the dry pipe and form a steam tight connection, while the middle compartment 5 is provided with a nozzle or extension 5^a which projects through the boiler shell and terminates in a flange. It will be 100 noted that the entire header structure is an integral casting of relatively thin flat configuration, vertically and centrally disposed in the smoke box with the discharge nozzle 5^a projecting up through the top of the 110

boiler shell. It will also be noted that the compartments 4 and 6 are in communication by means of a passage at the bottom of the header. In fact the compartments 4 and 6 with their connecting passage may be considered as but a single compartment surrounding the compartment 5 on three sides, all of the compartments lying in the same plane, and being disposed one behind the other in substantial alinement. 8 designates enlarged fire tubes or flues which extend from the fire box (not shown) to the tube sheet 7, and in these enlarged flues are disposed the superheater tubes 9. The side walls of compartments 4, 5 and 6 are provided with a number of openings 4', 5' and 6' with which openings the ends of the superheater tubes 9 communicate. The superheater tubes are of the double return bend type and are fitted with return bends 9^a and 9^b at their rear ends and with the return bend 9^c at their forward ends, thus making four lengths of tube in each flue. The two free ends of the tube in each flue are connected with an anchor block 10, two such adjacent blocks being spanned by a yoke 11, held in place by means of a bolt and nut 12, in a manner hereinafter described. Referring to Fig. 2 it will be noted that there are four vertical rows of enlarged flues on each side of my centrally disposed vertically extending header. In other words there are four such enlarged flues in each horizontal row on each side of the header. By reference to Fig. 1, it will be noted that two anchor blocks 10 lie in the same horizontal plane and that there are four such blocks opposite the end of each horizontal row of enlarged flues. Interference is prevented by virtue of the fact that the tubes from two of the flues are connected to the upper pair of blocks 10 while the tubes from the other two flues are connected to the lower pair of blocks. This is made possible by arranging the front return bend alternately at the upper and at the lower portion of the enlarged flues. It is thought this novel method of connecting the tubes to the header will be understood without further discussion. It results in reducing to a minimum the number of joints and bolts necessary to provide a given amount of heating surface and also enables any superheater unit to be readily removed without affecting any but its immediate neighbor. The details of the bolt and anchor blocks will be described in connection with Figs. 5 and 7.

Referring again to Fig. 1, 13 designates the usual stack, immediately behind which 60 projects the nozzle 5^a of the superheater header. Secured to and supported by this nozzle I provide the casing 14 of my improved throttle valve. This casing is provided with a flanged coupling 14^a adapted 65 to be bolted to the flange of the nozzle 5^a

and with a removable end wall 15 which carries a stuffing box 15^a, through which passes the operating rod 16 of the throttle valve. This valve is preferably of the balanced type and may comprise a pair of 70 disks 17, 18, separated by a ribbed body 19 and adapted to engage beveled seats formed in the ends of an internal casing 20. At each side the valve casing 14 is provided with flanged couplings 14^b, 14^c, to which steam pipes 21, 22 are adapted to be connected, such pipes extending down on each side of the boiler to the engine cylinders. It will be observed that the throttle valve and steam pipes leading to the cylinders are entirely 75 outside of the boiler shell, whereby ready access to the parts is afforded for inspection and repair. All of the joints are readily accessible without the necessity of going inside the boiler or smoke box. The operating 80 rod 16 may be connected with the cab by any suitable system of links and levers, it being possible in some instances to have the pull rod extend for a considerable distance 85 inside of the hollow hand rail (not shown) 90 which usually exists along the side of the boiler over the running board. In order that it may be possible to repack the joints or grind the seats of the throttle valve or 95 associated parts without the necessity for drawing the fire and waiting for the locomotive to entirely cool down as heretofore, I provide the end of the dry pipe 3 in the steam dome 2 with a cut off valve 23 having a stem 24 extending through a stuffing box 100 25 and terminating in a hand wheel 26. By turning the wheel 26 the valve 23 may be closed and thus steam may be entirely shut off from the superheater and throttle valve. Under normal conditions, however, it will 105 be noted that the throttle valve, instead of being located between the boiler and superheater as heretofore, is disposed between the superheater and engine, whereby, even when the throttle valve is closed, so as to shut off steam from the engine, the superheater is nevertheless filled with steam. This is desirable for the purpose of preventing burning 110 of the superheater tubes when the engine is coasting. In order to still further protect the tubes against burning I provide 115 means for causing a gentle circulation of steam through such tubes when the throttle valve is closed. Such means comprises a valve casing 27 in which is disposed a valve 120 28 which controls communication between a pipe 29 connected with the top of the boiler and a pipe 30 connected with the top of the superheated steam compartment 5 of the header. The valve 28 is controlled by a piston 31 which is adapted to be moved to the position shown in Fig. 4 by steam pressure entering through the pipe 30^a whenever the throttle is open, such pipe 30^a being 125 connected with one of the steam pipes, 130

such as 21. When the throttle is open therefore the valve 28 is held closed and communication between the pipes 29 and 30 is shut off. When, however, the flow of steam 5 through the superheater to the engine is interrupted by reason of the closing of the throttle valve, there is no longer any pressure applied to the piston 31 and the boiler pressure acting through pipe 29 against the 10 valve 28 serves to unseat the same. Thereupon a slow circulation of steam from the steam dome through the dry pipe 3, compartments 4 and 6 of the superheater, tubes 9, compartment 5, pipe 30 and pipe 29 back to 15 boiler is set up. Such circulation is due to the fact that the steam in compartment 5 being superheated is much lighter and has much greater elasticity than that in the steam dome and therefore tends to rise and 20 flow through the pipe 30. This movement keeps up a constant changing of the steam in the superheater tubes thereby producing a cooling action and preventing the excessive heating thereof. In this way I am enabled 25 to dispense with the dampers heretofore employed for controlling the draft through the flues when the engine is not using steam.

Referring to Figs. 5, 6 and 7 I have shown my three compartment header arranged as a "top header." In these views the compartments are designated by the numerals 32, 33 and 34, the compartments 32 and 34 in reality constituting but a single compartment, and entirely surrounding the 35 compartment 33, being separated therefrom by the dividing wall 35 (see Fig. 6). This header, however, has the same characteristics as that shown in Figs. 1 and 2, viz., the three compartments all lie in one plane 40 and extend parallel with each other and with the tube sheet. Moreover the header casting is a thin flat structure presented edgewise in the smoke box and the compartments lie one behind the other in substantial alinement. The front wall of this 45 header is designated by the reference character 36 and the top and bottom walls by the characters 37 and 38 respectively. Projecting centrally upward from the top wall 50 is a discharge nozzle 39 which is connected with a short length of pipe 40 extending up through the boiler shell and terminating in a flange 40^a, to which flange the flange 14^a of the throttle valve casing may be secured, 55 as in Fig. 1. The compartment 32 is provided with an intake nozzle 32^a adapted to engage the fitting 3^a of the dry pipe.

The arrangement of superheater tubes in 60 connection with the header shown in Figs. 5, 6 and 7 is substantially the same as that shown in Figs. 1 and 2 except that, of course, they are only on one side of the header, that is, at the bottom thereof. The same pairs of anchor blocks and yokes are, however, employed, and there are four enlarged 65

flues in each row, the front return bends being arranged alternately on opposite sides of the flues, as clearly shown in Fig. 7, in order that proper connection with the respective anchor blocks may be effected, as 70 described in connection with Figs. 1 and 2. As a result of the novel and characteristic arrangement of the superheater tube ends shown and described in connection with Figs. 1, 2, 5, and 7, it will be observed that 75 not only do the ends of each unit lie directly one behind the other, but that all four ends belonging to a pair of units are disposed in a row, one behind the other longitudinally of the boiler. It will also be noted that the 80 face of the header structure to which the superheater tubes are connected lies at right angles to the tube sheet, and that the enlarged flues are arranged in rows extending in a direction at right angles to such face 85 of the header structure.

The form of attaching device which I prefer to use for securing the tubes to the headers in all of the figures of the drawing so far described is shown in detail in Figs. 90 8 to 12 inclusive. Referring to these figures, into each of the openings, such as 4', 5', 6', in Fig. 1, or 37^a, in Fig. 6, I insert a tapering screw threaded sleeve or nipple 41. These nipples are screwed into the wall of 95 the header and have their outer ends projecting slightly therefrom; the outer end of each nipple is cut on a curve, such as indicated at 42 in Fig. 8, such curve being preferably a segment of a sphere. At the 100 end of each tube 9 is forged or otherwise formed a solid, thickened, enlarged portion 9^a, known as a ball connection. This thickened end is cut beveled on the inside thereof as indicated at 9^b to form a flaring mouth, 105 such mouth being of a size to receive the rounded edges of the nipple 41. When brought into engagement, such rounded edge contacts with the beveled edge of the tube in such a manner as to form a line joint, and, 110 by slightly grinding the parts together with emery, or the like, a close fitting steam connection is easily and effectively secured. The anchor blocks 10 are provided with 115 openings 10^b of a size adapted to permit the tubes 9 to pass freely therethrough, the enlarged ends 9^a of the tubes being engaged by seats in the face of the anchor block. Each anchor block 10 is also preferably provided 120 at its middle with a seat or depression 10^a adapted to receive a protuberance 11^a formed on each end of the yoke 11, to prevent slipping. Each yoke is clamped against the anchor blocks by means of a tap bolt 43 which is set into the wall, such as 125 38, of the header. By reference to Fig. 11 it will be noted that these bolts are preferably set into the header at a point opposite the partition walls thereof, such as 35, thereby insuring a good hold. After the bolt 43 130

is screwed into place it is slightly flattened on one side and a key 44 laid against the flattened portion, such key resting in a notch 45 nicked out in the header adjacent the bolt hole. After the key has been inserted, a lock nut 43^a is screwed down over the key so as to hold the parts in position. Thus the tap bolt is prevented from turning. The outer end of this bolt passes through the 10 yoke 11, which is held in place by means of a nut 12 screwed on the outer end of the bolt, a washer 44' being preferably interposed between the nut and yoke. It will be noted that the nut 12 is closed at its outer end, or, 15 in other words, is what is known as a blind nut, whereby the end of the bolt on which the screw threads are formed is protected from the corrosion of the cases.

Referring to Figs. 13 and 14 I have shown 20 still another form of header structure which, although different from those shown in the other figures, embodies many of their characteristics. Like those above described it consists of a thin flat casting set edge 25 wise in the smoke box perpendicular to the tube sheet and has the same vertically extending discharge nozzle 53 provided with the flange 53^a adapted to receive the throttle valve casing. Also, like the form of 30 headers, shown in Figs. 1 and 2, the header shown in Figs. 13 and 14 is centrally and vertically disposed and is adapted to have superheater tubes connected to both sides thereof. It will be observed that the corresponding 35 ends of a plurality of the superheater tubes are arranged one behind the other longitudinally of the boiler.

The header shown in Figs. 13 and 14 comprises wet and dry steam compartments 47 and 48, respectively, the compartment 47 having an intake nozzle 46 provided with a flange 46^a and adapted to be connected with the dry pipe 8. The compartment 47 is provided with a number of branches 49 and the 45 compartment 48 is provided with a number of branches 50, these branches projecting at substantially right angles to their respective compartments and lying parallel with each other. The side walls of these compartments are provided with openings 49^a and 50^a adapted to receive the superheater tubes. These may be held in place either by the tap bolt arrangement, above described, in connection with Figs. 8 to 12, inclusive, or 55 the tubes may be secured by means of through bolts in the manner covered by my co-pending application Serial No. 684,811, renewed March 19, 1912. If the tap bolt arrangement is employed the compartments 60 49 and 50 will be separated from each other by partition walls such as 35, in Fig. 6, but if the arrangement of my above mentioned application is to be employed the compartments will be separated from each other by 65 walls having open slots 51 extending there-

through to accommodate the bolts. This arrangement is shown in Figs. 13 and 14, and the through bolts are designated by the numeral 52. The same anchor blocks 10 and yokes 11 may, however, be employed. 70

If desired, the headers shown in Figs. 1 and 5 may also be designed for use with through bolts instead of tap bolts. In Fig. 15 I have illustrated how the structure of Figs. 5 and 6 can be modified so as to adapt 75 it for use in connection with the through bolts shown in Figs. 13 and 14 or covered by my above mentioned co-pending application. The change consists in providing the partition walls with open slots 54 80 through which the bolts may pass. This also has the advantage of preventing heat transfer between the saturate and superheated steam compartments.

It will of course be understood that my 85 improved throttle valve and my improved circulating device may be employed either independently or together in connection with any of the forms of header shown in the drawings, and also it is apparent that 90 my improved throttle valve arrangement can be advantageously employed even where no superheater is used, the dry pipe connecting directly with the valve casing. It is also obvious that inside steam pipes from 95 the valve casing to the engine cylinders may be employed instead of the outside pipes shown, if desired.

It will thus be seen that I have provided 100 an improved locomotive and superheater construction, the broad principles of which may be embodied in a number of different forms, and it is thought that the many advantages of my invention will be readily appreciated by those familiar with the requirements of such devices. 105

What I claim is:

1. The combination with a locomotive boiler having the usual smoke box and stack, of a superheater mounted in said smoke box, said superheater comprising a header having a single central discharge nozzle projecting up through the top of the boiler shell at a point behind the smoke stack, and a throttle valve casing detachably mounted on such projecting nozzle wholly outside of said smoke box. 110

2. In a superheater structure, the combination with a header having openings therein, of nipples screw threaded into said openings, superheater tubes having their ends formed to fit the projecting ends of such nipples and disposed in axial alignment therewith and means for clamping such tubes against said nipples so as to form a 115 steam tight joint. 120

3. In a superheater structure, the combination with a header having openings therein, of nipples screw threaded into said openings, superheater tubes thickened at their 125 130

ends and having the inside of such thickened ends cut to a beveled edge, the ends of said nipples being provided with a rounded edge, and adapted to engage the beveled edge of said tubes so as to form a line joint, and means for clamping said tubes against said nipples.

4. In a superheater structure, the combination with a header having openings therein, of nipples screw threaded into said openings, superheater tubes provided with solid enlarged and thickened ends, and having such ends internally beveled so as to form flaring mouths, the ends of said nipples being so formed as to fit within such beveled mouths to constitute a tight joint, and means for clamping said tubes against said nipples, such means comprising anchor blocks adapted to engage the enlarged ends 20 of said tubes.

5. In a superheater structure, the combination with a header having openings therein, of superheater tubes adapted to communicate with said openings, anchor blocks in- 25 closing the ends of such tubes, and means for clamping said anchor blocks to the header, such means comprising a tap bolt screwed into the header, a key for preventing rotation of said bolt, a lock nut for 30 holding said key in position, and a nut on the outer end of said bolt.

6. In a steam boiler superheater, a header structure consisting of an integral casting comprising a pair of substantially rectangular steam compartments, one of said compartments completely surrounding the other on all four sides thereof and both compartments lying in the same plane.

7. The combination with a locomotive boiler comprising the usual tube sheet and smoke box, of a superheater comprising a header structure located in said smoke box, said header comprising a central and a pair of side compartments, said side compartments being in communication with each other, all of said compartments extending

parallel with each other and with the tube sheet, and lying in the same plane, one behind the other, longitudinally of the boiler in substantial alinement.

50

8. The combination with a locomotive boiler comprising the usual smoke box and tube sheet, and flues set into said sheet, of a superheater comprising a header made up of an elongated central compartment extending parallel with the tube sheet, and an outer compartment substantially surrounding said central compartment, said header consisting of an integral casting of relatively thin, flat configuration extending 60 horizontally and transversely across the upper part of the smoke box and disposed edgewise therein with said compartments lying one directly behind the other in substantial alinement, longitudinally of the 65 boiler, and superheater tubes arranged within the flues and having their ends communicating with the respective compartments of said header.

9. The combination with a locomotive 70 boiler comprising the usual smoke box and tube sheet, and flues set into said sheet, of a superheater comprising a header made up of an elongated central compartment extending parallel with the tube sheet, and an 75 outer compartment substantially surrounding said central compartment, said header consisting of an integral casting of relatively thin, flat configuration disposed edge- 80 wise in said smoke box with said compartments lying one directly behind the other, in substantial alinement, longitudinally of the boiler, and superheater tubes arranged within the flues and having their ends communicating with the respective compartments 85 of said header.

In testimony whereof I affix my signature, in presence of two witnesses.

JULIUS KINDERVATER.
